MACHINE FOR MAKING METAL BINDING STRIPS

William Wakefield, Richmond, near Melbourne, Victoria, Australia, assignor to Overseas Machinery Company Proprietary Limited, Melbourne, Victoria, Australia

Application September 29, 1931, Serial No. 565,900, and in Australia October 22, 1930

32 Claims. (Cl. 153—2)

This invention has reference to an improved machine for manufacturing metal articles of angular and/or corrugated shapes such as the metal binding strips for boxes, cases or the like and has been devised to provide a machine that will be positive and automatic in operation, whereby during the passage of a flat band through the machine, the strips are formed continuously and in predetermined lengths from a roll or like supply of metal band such as hoop iron and finally ejected from the machine in a condition for immediate application to a case, crate or the like.

The product of such machine renders it possible to construct a case, crate or the like without nails, screws or other attaching means, and when completed, the said case or crate will have greater strength and less weight and bulk than the cases or crates at present in vogue.

By a binding strip is meant a metal member formed with teeth or serrations on one or both edges, which strip is bent to form a channel section with the teeth projecting inwardly to lie substantially parallel with a plain side of the strip or both penetrating and engaging portions of each strip may be provided with teeth if so desired, in which case, the respective rows of teeth or projections will lie apart and parallel or substantially parallel to each other.

It is also within the ambit of the present invention to make flat binding strips with teeth at each edge or in the longitudinal centre thereof and while angle strips are particularly for use on the corners of cases or crates, the flat strips will be for the purpose of binding cases and crates about the body portion.

An important feature of the invention resides in the fact that metal binding strips of any desired length and form may be made and will, in a sequence of co-related operations and from a metal strip, simultaneously manufacture two similarly shaped metal binding strips of equivalent lengths which, if necessary, may be passed to a box, case or the like making machine, wherefore in the teeth of the strips will be caused to enter the wood or fabric from which the case is made.

This invention has many objects and salient features of which the following are the most pertinent:—

(a) Means between die and tool members and feed-in rollers of the machine whereby lengths of blank strip metal are fed into the machine and are positioned to be acted upon by the alternate operations of dies and tools, permitting

of a wide variation of control means to suit the various shapes and lengths of binding strips for the particular shape and dimensions of boxes or cases to which the finished strips are to be attached.

(b) The provision of means within the machine to cut or shape fastening tangs on the strip and spaced mitres for angularly folding the strips whereby they will accommodate the corners of the box or case, and then subjecting the strip to the action of means for simultaneously cutting and folding teeth in such a manner that the predetermined length of strip is formed into two separate and corresponding metal strips which are ejected from the machine as the finished product.

(c) Means operating in the machine to cut the strip of metal into predetermined lengths, such lengths being subjected to the alternate action of dies and tools for forming fastening tangs and spaced mitre cuts for folding purposes together with independently operable means for cutting teeth along the longitudinal length of metal strip, the cutting of the teeth resulting in the division of the said strip into two corresponding shaped strips of equivalent length and shape and additional means are provided to fold the outside of the strips downwardly simultaneously with folding or turning the teeth downwardly, whereby the ejected finished product of the machine comprises the two channelled, shaped and toothed metal strips shaped from the single metal strip delivered into the machine.

(d) The provision of a master cam to control the feed-in of the predetermined lengths of metal strip, the contour of the cam being such that, in conjunction with the dies and tools of the machine, it governs the finished characteristics of the metal strip constituting the product of the machine so that a variation in the shape of the master cam effects a variation in the lengths of the finished metal strips.

(e) A toothed drum disposed and operating in a sub-press or like means, said drum being rotatable under gear control which is operatively connected with the gearing of the master cam, the toothed drum reciprocating in unison with the sub-press to operate alternately a nest of dies which are adapted to impart the required formation to the metal strip prior to the cutting of the teeth therein.

(f) The timing control means of the machine in which the gearing of the toothed drum and the master cam have an equal number of teeth equivalent to the number of strokes of the sub-

press to complete a finished strip, so that the rotation of the gearing is identical to impart the requisite feed in to the metal strips to position same in relation to the nest of dies which are operated by the toothed drum in conjunction with the sub-press whereby all the die operations are in synchronism with the feeding action of the master cam and its associated gearing.

(g) The provision of means to rotate the toothed drum in unison with the timing gear of the master cam, said means comprising a ratchet co-axial with the said drum and operable by means of a bell crank, the other end of which connects a similar timing ratchet adapted to 10 rotate the master cam which operates in conjunction with a stop member formed on the end of the actuating mechanism of a ratchet adapted to operate the feed-in rollers, the function of the master cam being that it controls the degree 15 of each stepped rotation of the feed-in rollers whereby the requisite lengths of metal strip are positioned on the die plate in synchronization with the operations of the toothed drum and associated dies and tools.

20 But in order to more readily understand the invention reference will now be made to the accompanying drawings in which:

According to this invention the machine for manufacturing channelled shaped and toothed metal binding strips for cases, crates or the like is provided with a main frame for supporting the mechanism comprising spaced vertical plates 5 and 6 which near the top are fitted with bearings 7 and 8 through which the main driving shaft 9 is disposed and supported, the outer ends of the shaft carrying flywheels 10 and 11, 100 one of which receives a belt for driving the machine.

At a convenient working height the machine is provided with a longitudinal bed 12 upon which the co-related and aligning die plates are 105 mounted over which the metal strip is passed to effect the manufacture of the metal binding strips.

The strip of metal *a* may be fed into the machine from a roll or any other suitable assembly supply of band or hoop iron, and is first passed into a throat 13 disposed at the front of and in alignment with upper and lower tensioned feeding rollers 14 and 15 mounted on spindles 16 and 17, the inner ends of which are 110 fitted with pinions 18 and 19 in mesh for driving purposes, the upper roller 14 being yieldably mounted by means of its journals 20 which are disposed in guideways 21 formed in the bearings 22, a spring or springs 23 being positioned 115 between the top of each journal 20 and the top plates 24 of each bearing 22 whereby the rollers are maintained in tension and consequently in feeding relationship to receive and deliver the metal strip into the machine.

The outer end of the lower roller spindle has mounted thereon a feeding ratchet 25 which is disposed in a reciprocating casing 26 carrying the pawl 27 adapted to actuate the ratchet 25, the said casing 26 having connected thereto a 130 link 28 depending from a pivoted link system 29, the top of which is pivotally connected to the lower end of a spring loaded and telescopic connecting rod 30, the casing 31 of which at its upper end is mounted on a crank 32 carried on the outer end of the main shaft 9.

Reciprocating motion is imparted to the link system 29 from the main shaft 9 through the telescopic connecting rod 30 while reciprocating motion is imparted to the actuating link 28 140 which is pivoted to the casing 26, such reciprocation causing the pawl 27 to rotate the ratchet 25 which imparts a stepped or intermittent rotation to the feeding rollers.

The circumference of the rollers is directly 145 relative to the feeding ratchet 25 so that each stepped rotation thereof delivers a predetermined length of metal strip between the said rollers on to the initial die plate 34 disposed in the bed of the machine.

This initial die plate 34 is adapted to co-operate with a nest of dies which are illustrated in Figures 1, 5 and 7, being in this instance three in all which comprise the left hand tang 5 fastening dies 37, the central mitre dies 36 and the right hand tang fastening dies 35.

Each of the dies 35, 36, 37 are carried on independently operable and spaced plates 38, 39 and 40 respectively which are mounted on 10 spaced spindles 41 having springs 42 thereon to yieldably support the said plates, the tops of which are formed with heads 43, 44 and 45.

Operating in conjunction with the nest of dies is a toothed drum 46 disposed and operating in 15 a sub-press 47, the casing 47a of which is slidably mounted in a guideway 48 attached to the adjacent vertical frame plate 5, the said casing 47a being suspended on a depending spindle 49 connected with the casing 50 of an eccentric 51 20 carried on the main shaft 9 of the machine.

As in accordance with accepted practice the 25 sub-press 47 reciprocates under the action of the eccentric 51 and thereby carries with it the toothed drum 46 the teeth of which are arranged in spaced circumferential relationship according to the particular characteristics of the finished binding strips, each drum tooth 53 being vertically disposed above and in alignment with one of the heads 43, 44 and 45 of the dies 30 and as illustrated there is one tooth 53 on the drum to each tang fastening die and two spaced teeth 53 acting in combination with the mitre dies, to effect the necessary spacing cuts in the 35 metal strip for angular folding purposes as will be hereinafter described.

The toothed drum 46 is rotated by means of a timing ratchet 55 co-axially mounted therewith on the outside of the sub-press casing, the 40 said ratchet 55 being mounted within a reciprocating casing 56 which carries the pawl 57, the casing connecting the upper end 58 of a bell crank 59, pivoted as at 60 to the roller bearing frame 22, the outer and lower end of the bell crank 59 pivotally engaging with a shackle 45 61 connected to a reciprocating casing 62 operating a pawl 62a in engagement with a timing ratchet 63 disposed and operating within the 50 said casing 62, the said ratchet 63 having an equal number of teeth to that of the drum ratchet 55, the ratchet 63 being mounted on a spindle 64 co-axial with and adjacent to a master cam 65, the spindle 64 being supported in the socketed extension 66 as illustrated in Figure 2.

The toothed drum 46 is rotated by its ratchet 55 under the action of the bell crank 59 which is actuated by the vertical reciprocation of the 55 sub-press 47 with which the ratchet 55 moves vertically in unison, so that the action of the bell crank 59 imparts an axial reciprocation to the ratchet casing 56 which operates the pawl 57 and thereby imparts a continuous stepped or 60 intermittent rotation to the said drum ratchet 56.

Similarly as the number of teeth in the timing ratchet 63 are equivalent to the drum ratchet 56, the bell crank 59 imparts a corresponding stepped or intermittent rotation to this timing ratchet 63 which thereby rotates the master cam 70 65, whereby the rotation of the timing ratchet 63 and the master cam is positively equivalent to and in synchronization with the stepped rotation of the ratchet 56 and toothed drum 46.

The master cam is designed so that each of its 75 undulatory surfaces represents a predetermined

number of teeth on the roller ratchet 25 and in this instance the cam is provided with four concentric and undulatory surfaces 68 as illustrated more particularly in Figures 9 and 10, the peripheral length of each concentric surface 68 determining the number of teeth to be selected on the roller ratchet 25, the actuating link 28 at its connection with the ratchet casing 26 is formed with an outwardly projecting stop member 70 vertically disposed above the undulatory face 68 of the master cam 65 whereby, during the reciprocating movement of the actuating link 28 in rotating the roller ratchet 25, its downward movement is limited and varied by means of the stop member 70 riding on the concentric surfaces 68 of the cam, so that the further the link descends the greater the number of teeth stepped around the ratchet 25 by its casing 26 and pawl, so that as the stop member 70 rides around the inner concentric cam surfaces 68a a greater number of teeth are stepped around the ratchet 25 than when the stop 70 is riding on the outer concentric surfaces 68.

In this manner the master cam 65 controls the feed-in of the metal strip and although the 100 roller ratchet 25 actually imparts the stepped rotation to the rollers 14 and 15, the degree of stepped rotation or angular displacement of this feeding ratchet 25 is controlled by the cam 65 as it limits and varies the downward travel of 105 the actuating link 28 (operated by the spring loaded connecting rod as previously described) by means of the stop member 70 riding on the cam surfaces 68 and 68a which correspondingly limits the swing or reciprocation of the ratchet 110 casing 26 so that it merely turns through an arc sufficient to step the exact number of teeth on the roller ratchet 25 according to the circumference of the feeding rollers is designed in relation to the feeding or roller ratchet 25 on the predetermined number of teeth on the said 115 ratchet 25 being stepped by the action of the master cam as described, the requisite length of metal strip is fed between the rollers 14, 15 120 on to the die plate 34.

The master cam 65 by regulating the actual length of metal strip fed into the machine provides the necessary synchronized positioning of each length of strip on the die plate 34 below 125 one of the dies 35, 36, 37 according to the operation to be performed and simultaneously with the length of strip becoming stationary on the die plate below the particular die, the sub-press 47 continues its downward movement 130 while the aligning tooth on the drum 46 assumes a vertical position and impinges on the head of the said die whereby the continued descent of the sub-press 47 causes the tooth to force the said die downwardly to stamp out the desired 135 shape on the metal strip by co-operating with the corresponding shape on the die plate, the positive and synchronized positioning of the metal strip in preparation for the die shaping action ensures that the said shapes are formed on the strip at the predetermined positions and also ensures the correct spacing between each shape so formed along the entire length of the metal strip.

The relationship between the timing ratchets for the toothed drum 46 and master cam 65 with the sub-press is such that the number of strokes by the press to complete the binding strips for a box or crate is equal to the number 140 145 150

of teeth in each of the co-related timing ratchets.

This associated timing relationship effects the synchronism between the operations of the toothed drum, sub-press and master cam and input rollers so that each die of the nest is operated alternately in the timed sequence with the intermittent lengths of metal strip positioned on the die plate, the teeth on the drum 10 being positioned in circumferential relationship to assume a vertical position and impinge on the head of the respective die synchronously with the positioning of the intermittent lengths of the metal strip during the descending movement of the sub-press which actually supplies the pressure to the respective heads 43, 44 and 45 of the dies which are forced down to punch out the particular shape in the metal strip through the female dies on the base plate.

20 It will be understood that a variation in the design of the concentric undulatory faces 68 of the master cam 65 and in the circumferential disposition of the teeth on the drum 46 will effect a corresponding variation in the feed-in of 25 the lengths of metal strip and in the sequence of operations by the nest of dies whereby the master cam and toothed drum are designed to determine the finished characteristics and lengths of the binding strips as manufactured 30 by the machine according to the size of box, case or crate to which the binding strips are to be attached.

Figures 5 and 6 illustrate more particularly the operative relationship between the toothed 35 drum 46 and the nest of dies 35, 36 and 37 which are operable in the manner previously described and yieldably mounted at each side on the spaced spring wound spindles 41 erected on the initial die plate 34.

40 The left hand tang fastening die 35 is fitted on its underside with a series of depending tools 45 shaped to cooperate with the female dies 81 formed in the die plate 34, the particular shape thereof being illustrated in Figure 6.

45 The strip of metal "a" is shown dotted in position on the die plate 34 so that when any of the respective dies 35, 36 operate the shape remaining is of a pattern representing the formation of the metal between the slots 81 of the 50 female dies.

As illustrated in Figures 23 and 24 the tools of this die 31 stamp out the centre opening 83, side tang cuts 84 and adjacent mitre cuts 85 for folding the shaped tangs 86, the retaining strips 87 for breaking off the tank portion of the strip after the completion of the whole strip for assembly purposes, the spaced tang fastening holes 88 and the arc cuts 89 on the edge of the body portion 90 of the strip, the 60 said fastening holes 88 being adapted to receive the edges 86a of the tangs 86 when the said tangs are in the folded and fastened position illustrated in Figure 26.

The two retaining strips 87 maintain the strip 65 in a complete length as illustrated until the actual assembly of a box or crate.

The mitre die 36 has operating in conjunction therewith two teeth 53 on the drum 46 so that in its sequence the said mitre die 36 operates twice before either of the left or right hand dies 70 35 and 37 may operate, the operation of the said mitre die 36 being adapted to stamp out the spaced folding or mitre cuts 92 on each edge of the metal strip "a", the spacing of the said cuts 75 92 being determined according to the sizes of

the box or case to which the finished strips are to be applied and the said strips are folded or bent at right angles at the mitre cuts 92 as illustrated in Figure 25.

The aligning spaced and depending tools 80 of the mitre die are correspondingly shaped to the female mitre dies 94 formed in the die plate 34 while a central tool co-operates with the middle die 95 to form a central hole or opening 96 in the metal strip in transverse alignment with the mitre edge cuts as illustrated in Figures 23 and 24.

The right hand tang fastening die 37 is of a similar construction to the left hand die 35 previously described but whereas the left hand die 35 on forming the fastening tangs does not sever the metal strip, this right hand die 37 during the continuous operation of the machine, forms the fastening tangs on the incoming length of strip while simultaneously cutting off the previously shaped and finished length of metal strip for passing to the teeth cutting and folding dies.

The right hand die 37 has a similar series of tools 99 depending from the floating plate 40 100 but the tools are reversely arranged to those of the left hand die, to co-operate with the female dies 100, formed in the die plate 34 in longitudinal alignment with the other female dies previously described.

In this instance, the central tool 100a which is shaped to correspond with the central female die 101 is formed at the outer end with narrow cutting off extended edges 102 which are adapted to pass into and through the similarly shaped portions 104 of the central female die 101, the cutting off portions of the die being of sufficient width to sever the metal strip while cutting the tangs.

The depending tools 99 stamp out the edge 115 mitre cut 106 for folding the tangs 107, the effective portions 108 of which are stamped out to enter when folded into the fastening holes such as 88 in the body portion of the strip.

Therefore the tang forming and cutting off 120 tools 99 and 101 respectively function to form the tangs 107 and cut off the previously finished strip (as illustrated at 110) the latter end of which has formed therein the fastening holes 88 and edge arcs 111 for receiving the tangs when 125 the strip is assembled, the cut out arc portions 111 being utilized to turn back the over-lapping portions such as 108, the tangs after same have been placed in the fastening holes 88.

The dies operate in the following manner as 130 the metal strip is passed through from left to right across the die plate 34, the right hand die 37 operates and cuts the fastening tangs 107 and then the left hand die 35 operates and cuts the tangs 86 and retaining strips 87, after which 135 the mitre dies 36 function twice to effect the mitre folding cuts 92 and then the right hand die 37 operates once more and cuts off the metal strip and simultaneously forms the fastening tangs on the incoming length of metal strip.

The strip of metal after being subjected to the initial action of the tang fastening dies, is delivered on to a die plate 115 positioned on the bed of the machine in alignment with the initial die plate 34, the said die plate 115 being disposed between the vertical frame plates 5 and 6 as illustrated in Figure 1.

The die plate 115 is adapted to co-operate with a series of die tools carried in the bed 116 of a centre press 117 slidably disposed in bracket 150

guideways 118 and 119 attached to the vertical frame plates 5 and 6, the centre press being suspended on a vertical spindle 120 in engagement with the casing 121 of an eccentric 122a carried on the main shaft 9 of the machine, whereby the said press 117 reciprocates vertically within the guideways 118 and 119 under the action of the eccentric 122, while the bed 116 of the press is slidably supported on spaced vertical spindles 122 positioned on the bed of the machine.

The die plate 115 is divided into three sections 124, 125 and 126, each of which is detachably mounted therein and is vertically disposed below a co-operative die tool carried in the bed 116 of the centre press 117, the previously shaped strip being first subjected to the action of a slot cutting die or tool 127 which is adapted to punch or stamp out a series of inclined 20 equally spaced slots along the longitudinal centre of the metal strip.

This slot cutting tool 127 is formed with a predetermined number of equally spaced and inclined teeth 128, depending from a block 129 attached to the bed of the press 117, these teeth 128 being of an equal inclined width and are in vertical alignment with corresponding shaped and inclined slots 130 formed in the foremost die plate section 124, which comprises the female section of this particular die.

The teeth 128 of the die tool 127 are rectangular in cross section to correspond to the shape of slots 130 whereby on the previously shaped metal strip passing over the die plate section 124, the press 117 descends and the inclined teeth 128 of the die tool 127 co-act with the similar inclined female die slots 130 to punch out a series of correspondingly shaped slots or holes along the longitudinal centre of the metal strip.

Figure 18 illustrates more particularly the manner in which the teeth 128 of the die tool 127 form the series of equally spaced inclined slots or perforations along the centre of the metal strip "a", the slots "b" being substantially in the form of a parallelogram and are equally spaced and inclined as illustrated in Figs. 18 and 19.

Disposed and operating in the bed of the press 117 adjacent to the slot cutting tool 127 is a combined teeth cutting and edge folding die 132.

The teeth cutting section 132a of this die 132 comprises a predetermined number of teeth 133 which are similarly shaped and equally spaced as the teeth 128 in the slot cutting tool 127 described, but in this tool there is one tooth less, the purpose of which will be hereinafter described, the teeth 133, however, are inclined in an equal inverse relationship to the slot cutting teeth 128 as illustrated in Figures 11, 18 and 19.

These teeth 133, are vertically disposed on the die, in alignment with co-operating slots 135 formed in the die plate section 125, the said slots being angular in shape and oppositely inclined to the slots 130 in the adjacent female section 124 of the die plate as illustrated in Figure 12.

The metal strip "a" after having the series of inclined and equally spaced slots "b" punched or stamped out along its longitudinal centre, in its next intermittent movement is delivered on to the adjacent die plate section 125 so that the metal sections "c" between the previously formed slots "b" are vertically disposed below the teeth

133 of the die whereby the press 117 in descending will cause the teeth 133 of the die to strike the said metal sections "c" between each previously formed slot "b" to form the pointed teeth "d" illustrated in Figure 19.

As the inclination of the previously formed slots "b" is equal and reverse to the inclination of the die teeth 133, each tooth 133 of the die, when in operation, descends on to a metal space or section "c" between two adjacent slots "b" and strikes diagonally whereby each tooth 133 strikes diagonally in alignment flush with the top of one slot "b" and with the bottom of the adjacent slot "b" so that, by the teeth 133 punching out diagonal slots "e" in the metal "b" between the previously formed inclined slots "b", correspondingly shaped but oppositely disposed teeth "d" are formed, each edge of the initial slots "b" forming one tapered side of the teeth, the shapes of which are completed by the diagonal slots "e" punched out by the die teeth 133, the inclination of which forms the teeth of similar pointed characteristics but oppositely disposed as illustrated in Figures 17, 19 and 23.

It is a salient feature that during, and by the teeth cutting operation described, the original metal strip "a" is simultaneously divided along its longitudinal centre into two similar and independent metal strips "g" and "h" shaped in the manner previously described with their inner adjacent edges formed with rows of correspondingly shaped but oppositely disposed pointed teeth "d", this result being achieved by means of the inclined relationship between the initial slots "b" and the teeth 133, whereby the diagonal cutting action of the said teeth 133, shapes the pointed teeth "d" in opposite formation and of equal pitch, while simultaneously forming the two rows of teeth thereby dividing the strip "a" into the two separate and similarly shaped strips "g" and "h".

The teeth cutting section 132a of the die 132 operates through a pressure plate 135a seating between the outer folding surfaces 136 of the die and normally flush with the bottom thereof, the said plate 135a being suspended on rods 137, depending from the head 138 of the teeth cutting die 132a, the rods 137 being under spring control as at 139 so that when the die descends, the pressure plate 135a bears on the metal strip "a" during the teeth cutting action described, the teeth 133 extending through aligning slots 141 in the pressure plate 135a during the said cutting, which simultaneous with the folding edges 136 of the die contact with the overlapping edges of the metal strip at each side thereof and fold or turn the said edges downwardly.

As illustrated in Figure 16, the width of the female section 125 of the die plate being such that an overlap "j" is provided at each side of the strip "a" whereby, on the folding edges 136 of the die contacting with the said overlaps "j", the latter are folded or turned down at right angles against the edges 138a of the female section 125 of the die, whereby, on the completion of all the simultaneous operations of the die 132, the previously shaped metal strip "a" is divided into two similar metal strips of angular cross section, with the upper edges provided with rows of equally spaced and pointed teeth arranged in opposite relationship to each other.

The pressure plate 135a ensures that the metal strips "g" and "h" remain on the die plate section 125 during the disengagement of the

teeth 133 and folding edges 136 of the die 132 from the metal strip after the completion of the respective operations described.

As previously described, there is one more tooth in the slot cutting tool 127 than in the teeth cutting die 132a, whereby an additional slot "b" is formed in the metal strip prior to the action of teeth cutting die and this additional slot in the continuous operation of the machine is utilized to receive a pilot punch 140, the function of which is to engage with the said end additional slot as illustrated in Figures 12 and 13 and in doing so correctly position the previous series of angular slots "b" in relation to the teeth cutting die 132a, whereby the metal sections between the said slots will be positively below the teeth 133 of the die 132a to ensure that the diagonal cut between the said metal between the slots is achieved without any mutilation and consequent waste of metal.

The pilot punch 140 is mounted on a rocking arm 141 carried on a transverse spindle 142, the inner end of which has fitted thereon a bell crank 142a, the upper end of said bell crank 142a engaging with an actuating arm 143 connected as at 143a to the bed of the centre press 117.

The pilot punch 140 is operated through the members described to engage and disengage with the slot in the metal strip, the said punch extending upwardly through the aligning female die slot 130 to engage with the additional slot "b" in the metal strip "a" in the correct timing in synchronization with the operation of the centre press and slot cutting die 127.

After the two corresponding strips "g" and "h" have been shaped into an angular formation with the upper edges thereof formed with the rows of pointed teeth, the said strips "g" and "h" are moved in the next intermittent step on to the adjacent female die section 126, which is channelled as at 145, illustrated more particularly in Figures 12 and 15, the sides 146 of the channelled formation 145 being disposed on the die plate section 126 in alignment with the folding sides of the adjacent section 125 so that the angular sides of the strips "g" and "h" ride thereon, with the toothed surfaces bridging the gap in the channel 145 of this section 126 of the die plate.

Operating in conjunction with this channelled section die 126 of the die plate is a teeth folding die 150 which is disposed in the bed of the press 117 adjacent the teeth cutting die 132a, the said die 150 being provided with an internal rectangular folding ledge 151 adapted to engage in a free sliding fit within the channel 145 so that when the press 117 descends, the folding ledge 151 of the die impinges on the rows of teeth "d" of the metal strips "g" and "h" and folds the said teeth downwardly at right angles against the inside portions of the channelled sides 146 as illustrated in Figure 15, so that the metal strips "g" and "h" are then shaped to form inverted channelled sections and in this finished shape are ready for ejection from the machine.

Spring controlled pressure plates 153 are disposed in the die on each side of the folding ledge 151 to maintain the strips in position on the channelled sides 146 of the female die, during the teeth folding operations and also during the disengagement of the co-operating dies.

The impetus of the incoming lengths of metal strip is sufficient to pass the completed strips 75 "g" and "h" in their inverted channelled shape

below a guide roller 155 to the discharge rollers 156 and 157, the upper roller 156 being tensioned by means of springs 158 disposed between the slideable spindle blocks 159 and the tops 160 of the roller bearings 161, the spindle blocks 159 being slideably disposed in the guideways 162 under the tension of the springs 158 as illustrated in Figure 4.

The lower roller 157 is in frictional contact with the upper roller 156, the said rollers being driven in synchronization with the intermittent motion of the feed rollers 14 and 15 by means of a horizontal connecting rod 164 pivotally mounted to the casing 26 of the feeding ratchet 25, said rod 164 extending across the machine to pivotally connect the casing 165 of a ratchet 166 mounted on the outer end of the spindle 167 of the lower discharge roller 157, whereby during each intermittent operation of the feed rollers 14 and 15 a corresponding intermittent motion is imparted to the discharge rollers 156, 157 through the members described. 95

The lower discharge roller 157 is formed with spaced circumferential grooves 168 around the face thereof in alignment with the channelled sides 146 of the folding die 150 whereby on the completion of the channelled strips "g" and "h" they are passed under the guide roller 155 to be discharged between the rollers 156, 157, each strip passing over the metal surface 169 adjacent each spaced circumferential groove 168, the intermittent rotation of the said rollers passing the said strips therebetween into a discharge chute 170 attached to roller bearings 161 as illustrated in Figure 4.

Figures 21 to 26 inclusive illustrate in detail the finished characteristics of the dual strips "g" and "h" manufactured simultaneously by the machine in the series of operations previously described in their sequence and it will be obvious that although the operations of the respective tang fastening dies and teeth forming dies have been described in detail as separate operations, during the continuous working of the machine, all the dies and tools are operating at once in their correct timing sequence so that the strips after being subjected to the tang fastening dies described are then subjected to the teeth forming and folding dies, while the mitre spacing and folding dies are operating to determine the size and length of the strips, after which the cutting off dies sever the strip and the strip then continues its intermittent stepped movements to the teeth cutting and the folding dies for completion, the central openings in the metal strips being provided to eliminate the formation of the pointed teeth, at the mitre folding and spacing cuts and the end tang fastening portions so as not to restrict the folding and fastening arrangement of the metal strips during assembly as illustrated in Figures 25 and 26.

A machine constructed, arranged and operating in the manner previously described to manufacture dual metal binding strips of any length and of any finished characteristics should be of great utility and it is not meant to be arbitrarily confined to the herein-described details but desire it to be understood that various improvements and modifications may be embodied without departing from the spirit and scope of the invention. 145

What I claim as my invention and desire to secure by Letters Patent is:—

- for binding together box, crate or like sections, comprising means to deliver predetermined lengths of metal strip into the machine, means to form right and left hand fastening tangs and 5 a plurality of spaced mitre cuts in the length of strip, means to simultaneously cut and fold rows of oppositely disposed teeth on said strip to form two separate and correspondingly shaped toothed binding strips from one length 10 of metal strip, means to sever the said strips after completion and means to eject the said strips from the machine. 15 80
2. A machine for manufacturing metal strips for binding together box, crate or like sections, comprising means to deliver predetermined lengths of metal strip into the machine, variable timing and control means to position the lengths of metal strip in relation to means for forming right and left hand fastening tangs and spaced 20 mitre cuts for folding purposes, means for forming rows of oppositely disposed teeth along the centre of the metal strip to divide the said strip into dual strips, and means to eject the dual strips from the machine as its finished 25 product. 90
3. A machine for manufacturing metal strips for binding together box, crate or like sections, comprising means to deliver a predetermined length of metal strip into the machine, cooperating dies and tools, between which said means position said strip, means to alternately operate the said tools in timed sequence to respectively form right and left hand fastening tangs and spaced mitre cuts in the said strip, independently operable means for cutting pointed and oppositely disposed teeth along the centre of the previously shaped strip to form dual strips, means to fold the marginal outer edges of the strips downwardly, means to fold the pointed teeth downwardly at right angles to the upper edges of the strips, and means to eject the strips from the machine in the form of inverted channelled shaped strips. 35 100
4. In a machine for manufacturing metal strips for binding together box, crate or like sections, a sub-press, a toothed drum disposed and operating in said sub-press, timing mechanism to control the rotation of said drum, a master cam and gearing cooperating with said timing mechanism and thus regulating the feed-in of metal strip to the machine, a nest of dies and tools disposed below the toothed drum to receive the lengths of metal strip, the rotation and reciprocation of the toothed drum in unison 45 with the sub-press being adapted to alternately operate the tools to impart the requisite shape to the metal strips, and means to form rows of oppositely disposed and pointed teeth along the centre of the strips. 50 105
5. In a machine for manufacturing metal strips for binding together box, crate or like sections, a sub-press, a toothed drum disposed and operating in said sub-press, a ratchet co-axially mounted with said drum, a bell crank connected to the ratchet, a similar ratchet having an equivalent number of teeth, to which the other end of said bell crank is connected, a master cam co-axially mounted with the last-mentioned ratchet, feed-in rollers for the metal strip, a time ratchet operating in conjunction with said feed rollers, actuating mechanism geared to the main shaft of the machine, and to said timing ratchet and connected with the latter, and a stop member formed on the end of 55 said actuating mechanism, said stop member 110
- being adapted to engage with the undulatory surface of the master cam to determine the degree of stepped rotation of the feed-in rollers. 6. In a machine for manufacturing metal strips for binding together box, crate or like sections, tensioned feed-in rollers, a timing ratchet, intermittently operating said rollers, a casing for said timing ratchet, a system of links having one end in engagement with the ratchet, a spring loaded and telescopic connecting rod, to which the upper end of said linkage is connected, a casing for said connecting rod, a main shaft for the machine, to which said casing is geared, a stop member mounted to the lower link of said linkage, which is pivoted to said timing ratchet casing, a master cam, the said stop member being adapted to engage with the undulatory face of said master cam, a ratchet mounted co-axially— 85 with said cam, a bell crank pivoted to said ratchet, a corresponding ratchet, and a toothed drum, mounted coaxially, a sub-press, and a nest of independently operable dies and tools supported in the bed of the machine, and above which is disposed said sub-press, said toothed drum being disposed and operating in said sub-press. 90
7. In a machine for manufacturing metal strips for binding together, box, crate or like sections, a master cam, a timing ratchet co-axial with and operating said cam, a bell crank pivoted to said ratchet, a sub-press, a toothed drum disposed and operating in said sub-press and having a spindle, a ratchet corresponding to said first ratchet and mounted on said spindle, feed-in rollers for the strips, a toothed ratchet mounted with said rollers, said master cam having a stepped undulatory surface with each concentric surface adapted to represent a predetermined number of teeth on said last-mentioned ratchet, which has a casing, a pivoted link attached to the casing of said last-mentioned ratchet, a stop member on said link to engage with the undulatory surface of the master cam, a main shaft for the machine, and means to actuate the said link in a reciprocating manner from said main shaft of the machine whereby the stop member varies and limits the movement of said link and the intermittent stepped rotation of the feed-in rollers, to adapt the machine for the production of various sizes of strips. 115 105
8. In a machine for manufacturing metal strips for binding together box, crate or like sections, a nest of dies and tools; a sub-press; a toothed drum disposed in said sub-press for alternately operating said nest of tools and dies; timing mechanism to control the rotation of the drum in synchronism with the delivery of predetermined lengths of metal strip between the dies and tools, which are adapted to form a plurality of spaced mitre cuts, fastening tangs, and retaining slots in the said strip; and means to form rows of pointed and oppositely disposed teeth along the centre of the previously shaped strip to divide the said strip into two correspondingly shaped strips. 130 115
9. In a machine for manufacturing metal strips for binding together box, crate or like sections, a nest of dies, each of which has a set of tools, a female die plate positioned below the nest of dies in the bed of the machine, a sub-press above the tools, a toothed drum disposed and operating in said sub-press, a head portion on each set of tools positioned respectively in vertical alignment with the spaced circumfer- 145 120
- 75 140

- 75 150

ential teeth on the drum, and means to time and control the descent of the sub-press and rotation of the toothed drum to cause the teeth thereof to alternately impinge on the respective heads of the tools and punch out corresponding shapes in a length of metal strip disposed between the said tools and the female die plate.

10. A machine for manufacturing metal strips for binding together box, crate or like sections, including a nest of dies having tools, a sub-press, a toothed drum disposed and operating in said sub-press, said tools functioning alternately and in timed sequence under the control of said toothed drum, a female die plate positioned below the nest of dies, means to deliver predetermined lengths of metal strip on to the female die plate, the tools in operation being adapted to cooperate with the female die plate, to shape the metal strip with right and left hand fastening tangs and spaced mitre cuts, and means to cut off the finished metal strip in predetermined lengths.

11. In a machine for manufacturing metal strips for binding together box, crate or like sections, a sub-press, a toothed drum co-operating therewith, a nest of dies operated by said drum, a head portion on each die, a series of shaped tools depending from each head portion, means for independently and yieldably mounting each die, a female die plate positioned below the nest of dies, the said die plate having openings similar in shape and in alignment with the respective tools, and means to deliver predetermined lengths of metal strip between the said die plate and nest of dies.

12. In a machine for manufacturing metal strips for binding together box, crate or like sections, a toothed drum, a nest of dies, each of which is provided with a head portion in vertical alignment with one or more teeth on said toothed drum, a sub-press casing in which said drum is disposed, a timing ratchet mounted co-axially with the toothed drum exteriorly of said sub-press casing, means for yieldably and independently mounting each die, feed-in rollers for the strips, a die plate positioned in the bed of the machine in transverse alignment with said feed-in rollers, and a series of tools depending from the head portions of said dies in vertical alignment with co-operative female openings formed in said die plate.

13. A machine for manufacturing metal strips for binding together box, crate or like sections, comprising a main shaft, a centre press driven in a vertical reciprocating manner from said main shaft, a series of co-acting die tools in the bed of the press, and a female die plate in the bed of the machine, with which said die tools cooperate to form rows of oppositely disposed and pointed teeth along the centre of a previously shaped metal strip.

14. A machine for manufacturing metal strips for binding together box, crate or like sections, comprising a main shaft, a centre press driven in vertical reciprocating manner from the main shaft, a series of co-acting die tools disposed in the bed of the press, and a female die plate positioned below the said tools, the initial tool of the series being adapted in operation to punch out a series of spaced and inclined slots along the centre of a previously shaped length of metal strip.

15. A machine for manufacturing metal strips for binding together box, crate or like sections, comprising a centre press having a series of die

tools in the bed thereof, one of which comprises a slot-cutting tool, a block on said tool, having a predetermined number of spaced and inclined teeth depending therefrom, a female die plate positioned below the die tools having formed therein a series of similarly inclined spaced slots in vertical alignment with the teeth of the slot-cutting die, said teeth in operation being adapted to cooperate with the inclined slots to punch out a series of spaced inclined slots along the centre of a length of previously shaped strip.

16. A machine for manufacturing metal strips for binding together, box, crate or like sections, comprising a sub-press, a tooth-cutting tool and a slot-cutting tool mounted adjacent each other in the bed of said sub-press, cooperating slot-cutting and tooth-cutting dies, said tooth-cutting die having a predetermined number of spaced depending and inclined teeth, the inclination of said teeth being opposite to the teeth of the slot-cutting tool to operate diagonally across the metal spaces between slots previously formed in a length of metal strip by the said slot-cutting tool, whereby the tooth-cutting die forms rows of pointed and oppositely disposed teeth along the centre of the strip, and means associated with the tooth-cutting die to simultaneously fold down a marginal edge at each side of the strip.

17. A machine for manufacturing metal strips for binding together box, crate or like sections as claimed in claim 16 in which the tooth-cutting die, adapted to form rows of pointed and oppositely disposed teeth along the centre of the length of metal strip, thereby divides the strip into two dual strips.

18. In a machine for manufacturing metal strips for binding together box, crate or like sections, a centre press, a slot-cutting tool and a tooth-cutting tool, carried on said press adjacent to each other, equally spaced and inclined teeth depending from the slot-cutting tool, similar teeth depending from the tooth-cutting tool but of opposite inclination to the slot-cutting tool, a female die plate disposed below the centre press, and its associated tools, to receive lengths of previously shaped metal strips, the said die plate having spaced sets of oppositely inclined slots in alignment with the teeth of each tool, and means associated with the tooth-cutting die to simultaneously fold down a marginal edge on each side of the strip.

19. A machine for manufacturing metal strips for binding together, box, crate or like sections, according to claim 16 in which said tooth-cutting die has a predetermined number of equally spaced and inclined teeth, the inclination of which is opposite to the teeth of the slot-cutting die, each tooth of the tooth-cutting die in operation being adapted to strike diagonally across the metal spaces between inclined slots previously formed in a length of metal strips by the slot-cutting die and thereby punch out a diagonal slot between each slot in the metal strip, the inclination of the slots being such that the remaining metal is formed into two rows of oppositely disposed and pointed teeth and the strip is divided into two dual strips.

20. In a machine for manufacturing metal strips for binding together box, crate or like sections, a main shaft, a centre press having a bed and driven in a reciprocating manner from said main shaft, a slot-cutting tool in the bed of the press, a tooth-cutting tool in said press,

- adjacent to said slot-cutting tool, a block in the tooth-cutting tool having a predetermined number of equally spaced teeth depending therefrom, the said teeth being opposite in inclination to the teeth of the slot-cutting die, a female die plate disposed in the bed of the machine below the centre press and associated tools, the said plate having a series of spaced slots in alignment with the teeth of the respective tools with the inclination of the said slots coincident with the teeth in the said tool, means associated with the tooth-cutting die to simultaneously fold down a marginal edge at each side of the previously shaped length of metal strip during the teeth cutting operation thereon, means to rigidly retain the metal strip in position on the female die during the teeth forming and cutting operations, and means associated with the centre press to fold down the previously formed rows of teeth to eject the metal strips from the machine in the form of inverted channelled shaped strips having inner depending toothed surfaces, spaced mitre cuts, and fastening tangs for uniting the strips when in an assembled position.
21. In a machine for manufacturing metal strips for binding together, box, crate or like sections, a centre press, a slot-cutting tool, a combined tooth-cutting and edge-folding tool, a tooth-folding tool, all mounted in said press, and a female die plate disposed below the centre press and in alignment with the tools mounted therein, the effective face of the die plate being less in width than the folding edges of the tooth-cutting tool, said folding edges being adapted to fold down the overlapping edges of a length of metal strip positioned on the die plate.
22. A machine for manufacturing metal strips for binding together box, crate or like sections, according to claim 21 in which said female die plate has a width such that a marginal overlap of metal strip is formed at each side thereof, whereby the folding edges of the combined tooth-cutting and edge-folding tool will impinge on the overlapping edges of the strip and fold the same downwardly against the sides of the die plate.
23. In a machine for manufacturing metal strips for binding together box, crate or like sections, a centre press, a slot-cutting tool, mounted therein, a tooth-cutting and edge-folding cutting tool and a tooth-folding tool, also mounted therein, a female die plate disposed below said tools, a channelled portion in said die plate below the tooth-folding tool to receive dual strips having rows of oppositely disposed and pointed teeth, formed therein by said tooth-cutting tool, the folding tool being adapted to co-operate with the channelled portion to fold the said teeth downwardly against the internal channelled sides of the die plate, and means to eject the dual strips from the machine.
24. In a machine for manufacturing metal strips for binding together box, crate or like sections, a centre press, a tooth-folding tool mounted therein, a channelled shaped female die plate disposed in the bed of the machine below the folding tool, a central ledge in said tool adapted to enter the channelled recess of the die plate to fold down oppositely disposed and pointed teeth formed on dual metal strips positioned on the die plate, means to rigidly retain the said strips in position on the surface of the die during the teeth folding operation, and means to eject the dual strips from the machine.
25. In a machine for manufacturing metal strips for binding together box, crate or like sections, a sub-press, a toothed drum, a nest of dies and tools independently operable by means of said toothed drum operating in conjunction with said sub-press, a female die plate disposed below the nest of dies and tools, the dies being adapted to form right and left hand fastening tangs and spaced mitre cuts in a predetermined length of metal strip, a central depending tool with a transverse extended portion equal in width to the metal strip on the die for forming the right hand fastening tang, the die plate in alignment with said tool having a corresponding opening to co-operate with said depending tool, to sever the said strip after it has been subjected to the action of all the dies and tools of the machine.
26. In a machine for manufacturing metal strips for binding together box, crate or like sections, a sub-press, a toothed drum, a nest of dies and tools independently operable by means of said toothed drum and sub-press, a female die plate disposed below the nest of dies and tools, said dies being adapted to form right and left hand fastening tangs and spaced mitre cuts in a predetermined length of metal strip, and means on the die for forming the left hand fastening tang, to form a retaining strip to maintain the tangs temporarily integral with the major portion of the strip.
27. A machine for manufacturing metal strips for binding together box, crate or like sections including a pilot punch, a slot-cutting tool, operating in conjunction therewith, a female die plate disposed below the slot-cutting tool, spaced inclined slots in the die plate in alignment with the inclined teeth of said cutting tool, a tooth-cutting tool cooperating with said slot cutting tool, a female die plate cooperating with said tooth-cutting tool, the pilot punch being timed to extend through one of the slots in the die plate to register with an additional inclined slot formed in a length of metal strip positioned on the said first-mentioned die plate to positively position inclined slots formed in the metal strip by the slot-cutting tool on said second-mentioned female die plate disposed below said tooth-cutting tool.
28. A machine for manufacturing metal strips for binding together box, crate or like sections according to claim 27 comprising a transverse spindle, a rocking arm carried on said spindle, on which arm said pilot punch is pivotally mounted, a bell crank fitted on the inner end of said spindle, and an actuating arm pivotally connected to the bell crank and to the bed of a center press for transmitting to the pilot punch the motion of the center press.
29. In a machine for manufacturing metal strips for binding together box, crate or like sections, tensioned discharge rollers, correlated dies and tools mounted in alignment therewith, a guide roller disposed in front of the discharge rollers, the upper of which is yieldably mounted, the lower roller being provided with a series of spaced circumferential grooves through which finished strips may be ejected into a delivery chute, feed-in rollers, and means to intermittently operate the discharge rollers in timed sequence with said feed-in rollers.
30. In a machine for manufacturing metal strips for binding together box, crate or like sections, a ratchet, a casing therefor, tensioned

feed-in rollers intermittently rotated by said ratchet, an actuating arm pivoted to the casing of said ratchet, a system of links pivoted to the upper end of the actuating arm, a main shaft, a 5 spring loaded telescopic plunger pivoted to said links and driven from the main shaft, a master cam driven by said main shaft, a stop member formed on the lower end of the actuating arm to engage at intervals with the undulatory surface of said master cam, a timing ratchet having a casing and co-axially mounted with the master cam, an actuating link pivoted to the casing of the timing ratchet, a similar timing ratchet, also having a casing, a bell crank 10 pivoted to the upper end of the actuating link and to the casing of said similar timing ratchet, a sub-press, a housing therefor, a toothed drum co-axially mounted with said first-mentioned timing ratchet and disposed in said housing of 15 the sub-press, means to operate the sub-press in a vertical reciprocation from the main shaft, a series of spaced circumferentially arranged teeth on said drum, a nest of dies and tools positioned below the toothed drum, a head portion on each 20 die in alignment with at least one tooth on the drum, feed-in rollers for the metal strips, an initial female die plate disposed below the nest of dies and tools to receive predetermined lengths of metal strip delivered thereon by the feed-in 25 rollers, a second female die plate positioned in 30

alignment with the initial die plate; a centre press mounted above said last-mentioned die plate, and having a bed, means to operate the centre press in a vertical reciprocation from the main shaft, a slot-cutting tool, a combined tooth-cutting and edge-folding tool, and a tooth-folding tool carried in the bed of the centre press, tensioned discharge rollers in alignment with the female die plates, and means to intermittently operate the said discharge rollers in synchronism with the feed-in rollers. 80 85

31. A machine for manufacturing a metal strip for binding together box, crate, or like sections, comprising means for feeding a strip, means for forming the strip into a substantially channel section, and means for forming teeth depending from one flange of the channel and a plain portion on the other flange. 90

32. A machine for manufacturing a metal strip for binding together box, crate, or the like sections, comprising means for feeding a single length of metal strip such as hoop iron, into the machine means for forming the strip into two similarly shaped strips of substantially channel cross section, and means for forming on each of 100 said last-mentioned strips, teeth depending from one flange of the channel and a plain portion on the other flange thereof. 95
